UNITED STATES PATENT OFFICE

169,301

WASTEBASKET

**Louis H. Barnett and Harris Brin,
Fort Worth, Tex.**

Application July 24, 1952, Serial No. 20,746

Term of patent 14 years

(Cl. D58—17)

To all whom it may concern:

Be it known that we, Louis H. Barnett and Harris Brin, both citizens of the United States, and both residing at Fort Worth, Texas, county of Tarrant, and the State of Texas, have invented a new, original, and ornamental Design for a Wastebasket, of which the following is a specification, reference being had to the accompanying drawing, forming part thereof.

Figure 1 is a perspective view of a wastebasket showing our new design.

Figures 2 and 3 are, respectively, front and side elevations thereof.

Figures 4 and 5 are, respectively, top and bottom views thereof.

We claim:

The ornamental design for a wastebasket, substantially as shown.

**LOUIS H. BARNETT.
HARRIS BRIN.**
